CLAIM

The ornamental design for a handle for parasol, as shown and described.

DESCRIPTION

FIG. 1 is a perspective view of a handle for parasol showing our new design;

FIG. 2 is a left side view thereof;

FIG. 3 is a right side view thereof;

FIG. 4 is a front view thereof;

FIG. 5 is a rear view thereof;

FIG. 6 is a bottom view thereof; and,

(Continued)

FIG. 7 is a left side view of the handle for parasol, shown in use attached to a parasol.
The broken lines depict environment that forms no part of the claimed design.

1 Claim, 7 Drawing Sheets
